ATTORNEY.

UNITED STATES PATENT OFFICE.

CHARLES DUBIN, OF PHILADELPHIA, PENNSYLVANIA.

HAND-TOOL FOR FORMING ORNAMENTAL LOOPS.

1,373,059.

Specification of Letters Patent. Patented Mar. 29, 1921.

Application filed November 18, 1919. Serial No. 339,226.

To all whom it may concern:

Be it known that I, CHARLES DUBIN, a former subject of the Emperor of Russia, residing at Philadelphia, county of Philadelphia, and State of Pennsylvania, have invented a new and useful Improvement in Hand-Tools for Forming Ornamental Loops, of which the following is a full, clear, and exact description, reference being had to the accompanying drawings, which form a part of this specification.

My invention is applicable to hand tools whereby yarn may be inserted through a fabric to form a series of loops upstanding on the face of the fabric and imparting thereto an ornamental effect. The object of the invention is to provide a simple and inexpensive construction whereby the size of the loops may be predetermined.

20 The invention is illustrated in the accompanying drawing, which is a longitudinal sectional view thereof.

A handle *a* has extending through it an axial orifice within which a needle *b* is fixedly positioned. The needle is of tubular form. One end of the tube projects beyond the forward end of the handle and is beveled at the end to form an exposed wall through which is formed an eye *c*.

30 To thread the needle the end of the yarn is secured to a wire. The wire is passed through the needle, carrying the thread with it. The thread is now detached from the wire and pulled through the eye.

35 In operating the tool, the threaded end of the needle is pushed back and forth through the fabric, forming a series of loops on one face and an ordinary sewing stitch effect on the other face.

40 In order to insure uniformity in the diameter of the loops, the shank of the needle, at each reciprocation, should be pushed through until the front end of the handle abuts against the fabric *x*.

45 In order to predetermine the diameter of the loops, there is provided a series of wash-

ers *d*, operating as gage members, one of more of which may be slipped onto the needle and against the end of the handle. To form a large loop none of the washers 50 is applied. To make a loop of the next smaller size, one washer is applied. Two or three washers are applied to make progressively smaller loops, while all four washers are applied to make the smallest 55 loops. It is obvious, of course, that any number of washers may be employed. It is obvious, also, that these washers form, in effect, an extension of the handle so far as the handle forms an abutment for the fabric. 60

It is important, in order to secure easy and certain operation, that the area of the abutment afforded by the front face of the handle should be relatively small and for this reason the front of the handle is narrowed in diameter relatively to the diameter of the main body of the handle. 65

It will be understood that, as the looping operation proceeds, additional yarn is being fed through the hollow handle and needle. 70

Having now fully described my invention, what I claim and desire to protect by Letters Patent is:

A tool for forming a series of ornamental loops on the face of the fabric, comprising a hollow needle and a handle into which the needle extends, the front end of the needle being beveled and projecting beyond the handle and the rear end of the handle having an opening to permit the passage of a 75 thread through the handle and the hollow needle to the beveled end thereof; and detachable gage members sleeved on the needle and movable against the front end of the handle and forming a continuation of the 80 handle, whereby a variable number of the gage members may be removed to predetermine the depth of penetration of the needle. 85

In testimony of which invention I have hereunto set my hand, at Philadelphia, Pa., 90 on this 18th day of November, 1919.

CHARLES DUBIN.
